UNITED STATES PATENT OFFICE.

JOHN G. IMFELD, OF ROCHESTER, NEW YORK, ASSIGNOR TO VACUUM OIL COMPANY, OF NEW YORK, N. Y., A CORPORATION OF NEW YORK.

BARREL-HOOP-DRIVING MACHINE.

1,411,436.

Specification of Letters Patent.

Patented Apr. 4, 1922.

Application filed August 2, 1920. Serial No. 400,635.

To all whom it may concern:

Be it known that I, JOHN G. IMFELD, a citizen of the United States, and resident of Rochester, in the county of Monroe and State 5 of New York, have invented certain new and useful Improvements in Barrel-Hoop-Driving Machines, of which the following is a specification.

The present invention relates to barrel 10 hoop driving machines, and an object thereof is to provide in connection with such machine a kick-off mechanism operating in timed relation to the hoop driving mechanism to kick the barrel off the support after 15 the hoop driving mechanism has operated.

To this and other ends, the invention consists of certain parts and combinations of parts all of which will be hereinafter described, the novel features being pointed out 20 in the appended claims.

In the drawings:

Fig. 1 is a vertical section through a hoop driving machine constructed in accordance with this invention, showing the barrel in 25 position ready to be kicked off after the completion of the hoop driving operation.

Fig. 2 is a fragmentary view showing the kick-off mechanism in the position it occupies immediately after kicking off the barrel;

Fig. 3 is a fragmentary section on the line 3—3, Fig. 1;

Fig. 4 is a detail view showing the connection between the hoop driving mechanism 35 and the kick-off mechanism;

Fig. 5 is a detail view of the guide for the weighted lever of the trip mechanism;

Fig. 6 is a detail view of the angled lever which connects with the kick-off device;

Fig. 7 is a fragmentary section of the trip lever; and

Fig. 8 is a sectional view of the trip lever in a position during its return movement.

The barrel 1 is supported upon a support 45 2 and a hoop driving mechanism of any suitable form operates upon the hoop of such barrel. In this instance, the hoop driving mechanism is supported by guides 3 and rods 3^a projected upwardly on opposite sides 50 of the support 2 and connected by a head frame 4 at their upper ends. Operating on the guides 3 is a driving head 5 which may be moved in any suitable manner as by a screw 6 operating in the head and turned alternately in opposite directions through a

bevel gear 7. This driving head carries a number of driving devices 8 preferably in the form of double arm levers pivoted at 9 to the head and having weights 10 thereon which tend to move their engaging ends 11 toward the center of the head 5. The other arms of these double arm levers cooperate with a cam ring 12 which may be adjusted to limit the inward movement of the engaging ends 11 and hold them properly positioned so as to pass over the end of the barrel. At the same time it permits the engaging ends to swing outwardly as the driving head moves downwardly. The ring may be turned to shift the engaging ends outwardly. 60 No claim is made per se to the driving mechanism hereinbefore described.

The feature of this invention is a kick-off mechanism operating in timed relation to the driving mechanism. This kick-off 75 mechanism embodies preferably a kick-off device 15 which, in this instance, is in the form of a U-shaped member having its ends pivoted at 16 on opposite sides of the support 2 so as to swing above and below the 80 supporting surface of said support. Normally this kick-off device lies in its lowermost position, being preferably held in such position by a spring 17 which is connected at 18 to a lever 19, this lever being pivoted 85 at 20 to brackets 21 supported to one side of the support 2. The upper end of this lever 19 is adjustably connected at 22 to a link 23, the latter in turn being pivotally connected at 24 to an angle lever 25 which is pivoted at 26 to guides 3. The angle lever 25 is pivotally connected at 28 to a link 29, the latter being in turn pivotally connected at 30 to one arm of the kick-off device 15. The kick-off device is operated by a trip mechanism 90 which, in this instance, comprises a trip device in the form of a lever 31 pivoted at 32 to a bracket 33 which by braces 34 connects with the bracket 21. This trip device has an end piece or portion 35 pivoted thereto at 36 and carrying a roller 37 which cooperates with a lateral arm 38 projected from the lever 19. The trip lever 31 turns about a different center from the lever 19 so that when the roller end of the trip lever 31 moves upwardly it will engage the free end of the arm 38 and swing the lever 19 on its pivot, thus operating the kick-off device 15. On the return movement of the lever 31, the pivoted end 35 thereof carrying the roller 110

37 passes by the arm 38 turning on the pivot 36 so that no movement is produced in the lever 19. Movement of the trip device 31 may be effected through a link 39 which is 5 pivoted at 40 to the trip lever 31 and at 41 to a double arm lever 42 which in turn is pivoted at 43 to a bracket 44 supported on one of the rods 3*. A weight 45 is mounted on the opposite end of the lever 42 so 10 that the trip device 31 is normally held in the position shown in Fig. 1. A guide 46 may depend from the head 4 of the frame and a pin 47 may cooperate with that portion of the lever 42 operating in the guide so 15 as to determine the initial position of the trip device 31, this pin being insertable in any one of the openings 48 provided in the guide 46.

In order to effect movement of the trip 20 device in timed relation to the driving head, the latter has an abutment 49 formed thereon and cooperating with the lever 42 after the driving head 5 has moved upwardly to a certain position to carry the driving device 25 out of the path of the barrel. It is apparent that the driving head 5 may move relatively to the lever 42 so as to effect the driving action as well as the carrying of the driving device out of the path of the 30 barrel. By shifting the pin 47 in the proper opening 48 in the guide 46, the time at which the operation of the kick-off device shall take place may be varied.

The operation of the invention will be 35 understood from the foregoing, but it may be summarized as follows:

The screw 6 is rotated in the proper direction to cause the descent of the head 5, thus carrying the driving device downwardly 40 and causing the hoop to be driven onto the barrel. After this action takes place, the screw 6 is rotated in the opposite direction, and when the head 5 has carried the driving device above the upper end of 45 the barrel, then the abutment 49 will cooperate with the lever 42 and turn said lever on its pivot 43. This swings the trip device in order to cause the roller 37 to cooperate with the arm 38 so that the lever 19 50 will swing on its pivot and carry the kick-off device upwardly into engagement with the barrel so as to eject the barrel from the machine. Later the roller 32 passes out of engagement with the arm 38, permitting the 55 lever 19 and the kick-off device 15 to return to their normal positions. Upon the descent of the driving head 5, the trip lever will move in the opposite direction and the portion 35 will swing on the pivot 36, permitting the roller 37 to pass the arm 38 without producing any movement in the lever 19 or the kick-off device 15.

From the foregoing it will be seen that there has been provided a hoop driving machine in which there has been incorporated

a kick-off mechanism operated in timed relation to the hoop driving mechanism. This hoop driving mechanism preferably embodies a kick-off device to which there is connected a lever engaged by a pivoted trip device, the trip device acting on the lever so as to operate the kick-off device when the trip device moves in one direction, provision being made whereby when the trip device moves in the other direction the lever will not be operated. The trip device is operated from the hoop driving mechanism and has such a connection therewith that it only operates the kick-off device after the hoop driving devices have passed out of the path 75 of the barrel on the support. 80

What I claim as my invention and desire to secure by Letters Patent is:—

1. A barrel-hoop driving machine comprising a horizontal support on which the barrel is adapted to be vertically arranged, a head movable vertically above said support, driving devices movable with the head toward and from the barrel on the support and also having a movement relatively to the head, a kick-off device operable to displace the barrel horizontally from the support, and mechanism for operating said kick-off device, controlled by said head in its movement away from the barrel, in order to effect 95 the operation of the kick-off device after the driving devices have been carried out of the path of the barrel by said head.

2. A barrel hoop driving machine comprising a support for the barrel, a hoop driving mechanism for operating upon a barrel 100 on the support, and a kick-off device of substantially U-shaped form pivotally mounted at opposite ends below the supporting surface of the support and movable upwardly 105 to kick a barrel off the support after the hoop driving mechanism has operated.

3. A barrel hoop driving machine comprising a support for the barrel, a hoop driving mechanism for cooperating with a barrel 110 on the support, a kick-off member for cooperating with a barrel on the support, a lever connected with said kick-off member, and a trip lever mounted to turn about a different center from that of the last mentioned 115 lever and operated in timed relation to the hoop driving mechanism, said trip lever having a portion which is adapted to pass the first mentioned member without operating the latter upon the return movement of 120 said trip lever.

4. A barrel hoop driving machine comprising a support for the barrel, a hoop driving mechanism for operating upon a barrel 125 on the support, a U-shaped kick-off member pivoted at its ends and adapted to cooperate with a barrel on the support, a lever connected with said U-shaped member, a trip lever mounted to turn about an axis different from the axis of turning of the last 130

mentioned lever and to cooperate with said last mentioned lever to move the latter in one direction, said trip lever having a portion adapted to pass said first mentioned lever without operating the latter when moved in the other direction, and means for operating said trip lever.

5 5. A barrel hoop driving machine comprising a support for the barrel, a hoop driving mechanism for cooperating with a barrel on the support, a U-shaped kick-off member pivotally mounted at its ends below the supporting surface of said support, a lever having a link connection with said kick-off member, a second lever having a link connection with the first mentioned lever, a trip lever arranged to cooperate with the second mentioned lever to move said second mentioned lever in one direction, and said 10 trip lever also having a portion adapted to pass the said second mentioned lever without operating the latter when moved in the other direction, and mechanism for operating said trip lever.

20 6. A barrel hoop driving machine comprising a support for the barrel, a hoop driving mechanism for cooperating with a barrel on the support, a kick-off device for kicking a barrel off the support, a spring acting 25 on said kick-off device to hold it away from the barrel, a lever connected with said kick-

off device, and a trip mechanism for operating the kick-off device, said trip mechanism embodying a lever which is mounted to turn about an axis different from the axis 35 of turning of the lever which is connected with the kick-off device, and said trip lever having a portion adapted to pass the first mentioned lever without operating the latter when moved in one direction so that said 40 first mentioned lever with the kick-off device may be returned to normal position prior to the return to normal position by the trip mechanism.

7. A barrel hoop driving machine comprising a support for the barrel, a hoop driving mechanism including a vertically movable head carrying means for cooperating with a barrel on the support, a kick-off device for kicking a barrel off the support, a 50 lever connected with said kick-off device, and a trip mechanism for operating said lever, said trip mechanism including a trip lever for cooperating with the said first mentioned lever, and a pivoted, weighted 55 lever connected with the trip lever and arranged in the path of the head to be engaged by the latter during its movement in order to effect the operation of the trip lever to cause the operation of the kick-off device. 60
